Thomas M. Steinbach, Park Ridge, Ill., assignor to
General Electric Company, a corporation of New York

Filed Dec. 31, 1962, Ser. No. 73,025

Term of patent 14 years

(Cl. D52—7)

Fig.1.

Fig.2.

Fig.4.

Fig.3.

FIG. 1 is a front elevational view of a thermostat or the like showing my new design;

FIG. 2 is a side elevational view as seen from the left of FIG. 1;

FIG. 3 is a plan view thereof; and

FIG. 4 is a perspective view thereof.

The undisclosed side of the thermostat is substantially the same in appearance as the side shown in FIG. 2.

I claim:

The ornamental design for a thermostat or the like, substantially as shown and described.
